DESIGN FOR LACE

Max U. Juestrich, Ridgefield, N. J., assignor to
The American Fabrics Company, Bridgeport, Conn., a corporation of Connecticut

Application July 12, 1941, Serial No. 102,093

Term of patent 3½ years

To all whom it may concern:

Be it known that I, Max U. Juestrich, a citizen of the United States, residing at Ridgefield, county of Bergen and State of New Jersey, have invented a new, original, and ornamental Design for Lace, of which the following is a specification, reference being had to the accompanying drawing,
forming part thereof.

The figure is a plan view of a piece of lace, showing my new design, the same being depicted on a dark background for the purpose of bringing out more clearly the details of the design.

I claim:

The ornamental design for lace, substantially as shown and described.
